UNITED STATES PATENT OFFICE.

DANIEL WILDE, OF WASHINGTON, IOWA.

GRAIN-ELEVATOR.

SPECIFICATION forming part of Letters Patent No. 508,070, dated November 7, 1893.

Application filed March 24, 1893. Serial No. 467,461. (No model.)

To all whom it may concern:

Be it known that I, DANIEL WILDE, a citizen of the United States, residing at Washington, in the county of Washington and State of Iowa, have invented a new and useful Grain-Elevator, of which the following is a specification.

This invention relates to grain elevators; and it has for its object to provide an improvement in grain elevators of the type set forth in my former Patent No. 442,159.

To this end the invention primarily contemplates an improved grain elevator which shall be so constructed as to be capable of convenient use with thrashing machines or separators, so as to embrace the same and to be so disposed with relation thereto as to conveniently combine the weighing and conveying of the grain, as it leaves the separator, by a single continuous operation.

With these and many other objects in view which will readily appear as the nature of the invention is better understood, the same consists in the novel construction, combination and arrangement of parts hereinafter more fully described, illustrated and claimed.

In the accompanying drawings:—Figure 1 is a perspective view of the grain elevator constructed in accordance with this invention, embracing a thrashing machine frame. Fig. 2 is a side elevation thereof showing a portion of a thrashing machine frame embraced by the elevator. Fig. 3 is a vertical sectional view of the elevator.

Referring to the accompanying drawings, A represents an endless tubular elevator frame comprising the opposite tubular legs B, connected at their lower ends by the horizontal tubular base C, open at its top as at D, and connected at their upper ends by the upwardly inclined top members E, meeting at a point in a line with the vertical center of the open tubular frame A, so as to form an inverted V-shaped top member for the vertical frame, that is designed to span and project above the deck of the thrashing machine or separator, which the frame embraces as clearly illustrated in the drawings.

The construction of the endless frame may also be described as a rectangular tubular frame having an inverted V-shaped top portion, said rectangular frame being made of

such a size and shape as to fit completely around the frame of a thrashing machine, so as to dispose the apex of the angular extension of the frame a suitable distance above the deck of the thrasher, thus leaving sufficient space for conveniently arranging the auxiliary devices used in connection with the endless frame. When the elevator frame embraces the separator machine, the open tubular base C, is disposed in such a position directly below the grain board of the separator, so as to receive the grain as the same is separated in the machine, and at the apex of the elevator frame which may be designated, as F, is arranged the top discharge opening G, at each side of which are arranged the inclined discharge boards H, which are intended to direct the grain into the weighing devices to be presently referred to.

At each angle of the open or rectangular tubular frame A, are mounted the chain or sprocket wheels I, over which passes an endless elevator or carrier chain J, to which chain are attached the buckets K, which serve, according to the direction of movement, to carry the grain from the open base portion C, of the frame, up through either leg thereof and to drop it through the top apex discharge opening G, motion being communicated to the endless chain by suitable belting in the ordinary manner.

As described, the specific construction of the frame with the angular extension at the top, provides a construction whereby a grain weigher L, can be conveniently clamped in position in the angle of the inverted V-shaped top portion between the members E, forming such top portion, so that as the grain is dropped from the carrier through the top discharge opening G, the same passes into the automatic weigher L, and is accurately weighed and registered, passing out of said automatic weigher onto the incline chute board M, disposed centrally and at an angle from one side of the transverse conveyer box or trough N. The transverse conveyer box N, extends transversely across and at one side of the tubular frame, and incloses a suitable conveyer O, which serves to convey the grain, which has been weighed, to either side of the separator machine to the bagging devices or directly into the wagons. It is of course understood

that any suitable form of conveyer such as a screw conveyer, instead of the endless conveyer illustrated, may be employed in connection with the transverse conveyer box or trough, or the box may be arranged at an incline and given a shaking or vibratory motion to work the grain out at its lowest end.

Now from the foregoing it is thought that the construction, operation, and the many advantages of the herein-described grain elevator will be readily apparent to those skilled in the art, it being readily seen that by the specific construction and arrangement of parts, an efficient apparatus is provided for elevating, weighing, and conveying the grain directly from the machine in which it is separated from other matter.

Changes in the form, proportion and the minor details of construction as embraced within the scope of the appended claims may be resorted to without departing from the principle or sacrificing any of the advantages of this invention.

Having thus described my invention, what I claim, and desire to secure by Letters Patent, is—

1. In a grain elevator, the tubular frame having an angular extension at the top and provided with a discharge opening at its apex, the endless carrier moving inside of said frame, and a separate and independent conveyer supported at one side of the tubular

frame and disposed under the apex discharge opening thereof, substantially as set forth.

2. In a grain elevator, the combination of the tubular frame having an angular extension at the top and provided with a discharge opening at its apex, an endless carrier moving through the frame, an automatic grain weigher arranged within said angular extension and disposed directly under the apex discharge opening, and conveying devices arranged under the grain weigher, substantially as set forth.

3. In a grain elevator, the combination of an open tubular frame having an angular extension at the top and provided with a discharge opening at its apex, and endless bucket carrier moving through the frame, an automatic grain weigher disposed at the top of the frame directly under the apex discharge opening, a transverse conveyer box or trough arranged at one side of the tubular frame and having an off-standing inclined chute board disposed under the discharge of the grain weigher, and suitable conveying devices in said box or trough, substantially as set forth.

In testimony that I claim the foregoing as my own I have hereto affixed my signature in the presence of two witnesses.

DANIEL WILDE.
